US00D533613S

(12) United States Design Patent (10) Patent No.: US D533,613 S
(45) Date of Patent: * Dec. 12, 2006

(54) PUTTER HEAD FACE

(75) Inventors: Wayne H. Byrne, Murrieta, CA (US);
Ronald K. Hettinger, Oceanside, CA
(US); Lionel Poincenot, Carlsbad, CA
(US)

(73) Assignee: Callaway Golf Company, Carlsbad,
CA (US)

() Term: 14 Years

(21) Appl. No.: 29/246,573

(22) Filed: Apr. 24, 2006

(51) LOC (8) Cl. 21-02

(52) U.S. Cl. D21/759

(58) Field of Classification Search D21/736-759;
473/324-331, 340, 341, 251-256

See application file for complete search history.
